BOTTLE

William A. Turner, 205 Sycamore Road,
Franklin, Va. 23851

Filed Nov. 23, 1970, Ser. No. 26,140

Term of patent 14 years

Int. Cl. D9—01

U.S. Cl. D9—160

FIG. 1 is a plan view of a bottle embodying my new design;

FIG. 2 is a side elevational view thereof taken on line 2—2 of FIG. 1;

FIG. 3 is another side elevational view thereof taken on line 3—3 of FIG. 2;

FIG. 4 is a view of the under surface thereof; and

FIG. 5 is a perspective view thereof.

I claim:

The ornamental design for a bottle, as shown.
